CLAIM

The ornamental design for a hand-held shower head, as shown and described.

DESCRIPTION

FIG. 1 is a front perspective view of a hand-held shower head showing our new design in full lines with the broken lines showing environmental association matter being for illustrative purposes only and forming no part of the claimed design.

FIG. 2 is a front elevational view thereof;

FIG. 3 is a left side elevational view thereof, with the right side elevational view being a mirror image thereof;

FIG. 4 is a top plan view thereof;

FIG. 5 is a bottom plan view thereof; and,

FIG. 6 is a back elevational view thereof.
